UNITED STATES PATENT OFFICE.

ARTHUR A. CRUSIUS, OF NEW YORK, N. Y.

AIR-INLET DEVICE.

1,313,584.

Specification of Letters Patent. Patented Aug. 19, 1919.

Application filed February 12, 1917. Serial No. 148,055.

To all whom it may concern:

Be it known that I, ARTHUR A. CRUSIUS, a citizen of the United States of America, residing at New York city, Manhattan borough, county and State of New York, have invented certain new and useful Improvements in Air-Inlet Devices for Internal Combustion Motors, of which the following is a full, clear and exact description.

10 This invention relates to a device for the admission or introduction of air to the combustible mixture created in the mixing chamber of the carbureter of an internal combustion motor; in other words, my invention 15 proved device, which consists partly of an auxiliary air-inlet-valve, is arranged to permit air to be drawn into the duct through which the combustible mixture is drawn by the suction of the pistons of a motor. The 20 device also includes a perforated chamber arranged for insertion into the passage through which the combustible mixture passes. The said chamber can be inserted into the neck of a carbureter, or carried by 25 a gasket-plate to be inserted between the flange of a carbureter and the flange of an intake-manifold, the valve being in communication with said chamber. The perforated chamber is arranged to admit air in 30 proportion of the speed of the motor. In other words, at low speed the motor will draw less air than at high speed. The combined area of the openings in the chamber will be sufficient to admit the maximum 35 amount of air required. The amount of air drawn through the openings in the chamber will be dependent upon the speed of the motor.

I will now proceed to describe my invention 40 in detail, the novel features of which will be summarized in the appended claims, reference being had to the accompanying drawing, forming part hereof, wherein—

Figure 1 is a diagrammatic side view of a 45 portion of a carbureter and intake-manifold, my improved device being illustrated as inserted between the carbureter and manifold;

Fig. 2 is a similar view, illustrating the 50 device as applied directly to the neck of a carbureter, the manifold being omitted;

Fig. 3 is an enlarged detail view illustrating a gasket-plate having applied thereto my improved auxiliary air-chamber and a 55 valve in communication therewith; and

Fig. 4 is an enlarged fragmentary sec-

tional detail view, the section being taken on a line 4—4 in Fig. 3.

As herein embodied my invention consists of a chamber 5, which I term the auxiliary air-chamber, which is preferably inserted in the passage or opening 6 of a gasket-plate 7 to be inserted between the flange 8 of a carbureter 9 and the flange 8a of an intake manifold 10, as shown in Fig. 1, or 60 into the neck of said carbureter, as in Fig. 2. The device is equally efficient in both instances, the gasket-plate being employed on account of ready attachability to carbureters already installed. The invention resides 65 chiefly in the combination of elements regardless of point of attachment; but, as before stated, I preferably employ a gasket-plate.

In combination with the inserted air-chamber 5, I employ an air inlet-valve, said valve 12, being preferably of a construction described in my copending application for patent, Serial No. 137,539, filed December 18, 1916; but, for the sake of clearness, I will 75 briefly describe said valve. The valve 12 consists of a body portion 13 having a chamber 14 communicating with a duct 15 through which air is drawn by the suction of the motor-pistons, a ball-valve in this instance being employed to close the duct 15. To regulate the vertical movement of the valve 16 I employ a screw-threaded spindle 17. A duct 18 places the chamber 14 in communication with the chamber 5. The chamber 5 comprises (in this instance) a substantially semi-cylindrical hollow ring 19 having slots or openings 20 in the wall thereof, said openings being directed toward the center of the ring or duct through which the combustible mixture passes on its way to the motor. The ring or chamber 5 (as is evident) is located in the central opening 6 of the plate 7, or may be located directly in the neck of the carbureter, the wall of said opening in the 80 said plate or in the neck of the carbureter forming the outer wall of the bore 21 of the chamber.

It is quite evident that the suction of the motor will draw air through the slots or openings 20 to be mixed with the mixture drawn from the carbureter. At slow speed air will be drawn in through some of the openings 20; in other words, the suction of the motor, at slow speed, will not be 105 great enough to fill the bore of the chamber 5 with air drawn in through the valve 12

and the air drawn in will very likely be drawn in through those openings adjacent to the duct 18. At high speed, however, air will be drawn into chamber 5 through all 5 of the openings 20 and hence will be thoroughly mixed with the combustible mixture drawn from the carbureter.

As stated, a greater speed of the motor will correspondingly increase the indraft of 10 air and will bring more of the openings 20 into play. The air thus drawn in is subjected to frictional resistance from the walls of these openings to a much greater extent than if entering through a single tube or 15 passage of capacity equal to that of the aggregate of said small inlets. This will have a certain braking effect increasing with the speed of the motor and the number of such openings brought into use, and such braking will make for steadiness, preventing sudden changes of speed from causing irregular action and obviating all disadvantage by disturbance of the valve in its functions due for example to running over rough 20 roads.

What I claim as my invention is:

1. An auxiliary air inlet for internal combustion engines, an intake duct for the engine, a ring U shaped in cross section and 30 snugly fitting within the intake duct forming between the wall of said duct and said

ring an annular chamber, ports in said ring leading from the chamber to the intake duct and an inlet through the wall of said duct communicating with said chamber. 35

2. An auxiliary air inlet for internal combustion engines, comprising a gasket-plate having a central passage therethrough and a ring U shaped in cross section snugly fitting within the gasket-plate opening and 40 forming therein an annular chamber, said ring provided with a plurality of openings leading from the chamber to said central passage and an inlet leading to said chamber. 45

3. An auxiliary air inlet for internal combustion engines, comprising a gasket-plate having a central passage therethrough and a ring U shaped in cross section snugly fitting within the gasket-plate opening and 50 forming therein an annular chamber, said ring provided with a plurality of radially arranged slotted outlets leading from the chamber to the central passage and a single inlet leading to said chamber. 55

Signed at New York city, N. Y., this 10th day of February, 1917.

ARTHUR A. CRUSIUS.
